ATTORNEY'S

UNITED STATES PATENT OFFICE.

CLAYTON F. WETMORE, OF JERSEY CITY, NEW JERSEY, ASSIGNOR TO NATIONAL CASKET
MANUFACTURING CO., OF NEW YORK, N. Y., A CORPORATION OF NEW YORK.

DESIGN FOR A NAME-BLOCK OR SADDLE FOR CASKETS, COFFINS, OR SIMILAR ARTICLES.

No. 39,691.

Specification for Design.

Patented Dec. 15, 1908.

Application filed August 25, 1908. Serial No. 450,257. Term of patent 14 years.

To all whom it may concern:

Be it known that I, CLAYTON F. WETMORE, a citizen of the United States, residing at Jersey City, in the county of Hudson and State of New Jersey, have invented a new, original, and ornamental Design for Name-Blocks or Saddles for Caskets, Coffins, or Similar Articles, of which the following is a specification, reference being had to the accompanying drawing, forming a part thereof.

Figure 1 is a perspective of a name block showing my design.

I claim:

The ornamental design for a name block or saddle for a casket, coffin or similar article as shown.

CLAYTON F. WETMORE.
